US00D927810S

(12) **United States Design Patent** (10) Patent No.: **US D927,810 S**
 Lange (45) Date of Patent: **** Aug. 10, 2021**

(54) **DIRECTIONAL ARM FOR A VACUUM CLEANER TUBE**

(71) Applicant: **LANGE CHRISTIAN SA**, Andenne (BE)

(72) Inventor: **Christian Lange**, Ohey (BE)

(73) Assignee: **LANGE CHRISTIAN SA**, Andenne (BE)

(**) Term: **15 Years**

(21) Appl. No.: **35/507,903**

(22) Filed: **May 7, 2019**

(80) **Hague Agreement Data**

Int. Filing Date: **May 7, 2019**

Int. Reg. No.: **DM/204139**

Int. Reg. Date: **May 7, 2019**

Int. Reg. Pub. Date: **Nov. 29, 2019**

(30) **Foreign Application Priority Data**

Nov. 7, 2018 (EM) 005818879-0001

(51) **LOC (13) Cl.** **15-05**

(52) **U.S. Cl.**
